UNITED STATES PATENT OFFICE

SYLVAN REIS, OF BROOKLYN, NEW YORK

DESIGN FOR A TOY LAMP OR SIMILAR ARTICLE

Application filed January 30, 1932. Serial No. 42,681. Term of patent 3½ years.

To all whom it may concern:

Be it known that SYLVAN REIS, a citizen of the United States and resident of Brooklyn, in the county of Kings, city and State of New York, has invented a new, original, and ornamental Design for Toy Lamp or Similar Article, of which the following is a specification, reference being had to the accompanying drawings, forming part thereof, in which,

Fig. 1 is a perspective view of a toy lamp embodying my new design; and

Fig. 2 is another perspective view thereof showing the same in open position.

A dominant feature of the design is the provision of a toy lamp comprising a toy house provide with a door opening and a roof which may be opened and a tubular lamp within the house which may be seen through the door opening.

I claim:—

The ornamental design for a toy lamp or similar article, substantially as shown and described.

Dated, January 29, 1932.

SYLVAN REIS.
